UNITED STATES PATENT OFFICE.

NOAH S. HARTER, OF WAUKEGAN, ILLINOIS, ASSIGNOR, BY MESNE ASSIGNMENTS, TO THE FULTON COMPANY, OF KNOXVILLE, TENNESSEE, A CORPORATION OF MAINE.

THERMOSTATIC VALVE.

1,220,985.

Specification of Letters Patent. Patented Mar. 27, 1917.

Application filed February 9, 1914. Serial No. 817,636.

To all whom it may concern:

Be it known that I, NOAH S. HARTER, a citizen of the United States, residing at Waukegan, in the county of Lake and State of Illinois, have invented certain new and useful Improvements in Thermostatic Valves, of which the following is a specification.

One of the objects of my invention is to provide an automatic, thermostatic valve, 10 controllable by the expansive effect of a fluid confined within a suitable receptacle, from which substantially all of the air has been removed, whereby to utilize the sensitive expansibility of a fluid to move a valve part when said fluid is under less than atmospheric pressure.

Another object of my invention is to provide, in a device of this character, a valve moving part, movable by the effect of outside pressure in one direction, to open the valve, and movable in another direction by the expansion of a medium normally under less than atmospheric pressure, to close the valve.

25 And another object of my invention is to provide means whereby the valve is automatically closed in the event of a leak of the liquid, or gas evolved therefrom, from said receptacle.

30 Other and further objects of my invention will become readily apparent to persons skilled in the art from a consideration of the following description when taken in connection with the drawings, wherein—

35 Figure 1 is an elevation of a coffee urn showing my thermostatic gas valve applied thereto.

Fig. 2 is a central vertical section of the thermostatic valve.

40 Fig. 3 is a section taken on line 3—3 of Fig. 2.

Fig. 4 is a section of a modification consisting of a housing for inclosing the heat responsive, thermostatic device to protect it 45 against extraneous influences, and means for holding the same in contact with the outer surface of the coffee urn or like device that is to be heated by the gas or other fluid controlled by said valve.

50 In all the views the same reference characters are employed to indicate similar parts.

Referring specifically to the valve, and its mode of operation, a two part casing 5 having a removable cover 6 contains a dia-

phragm or resilient wall 7, which divides the 55 casing into chambers 8 and 9.

The casing contains another chamber 10, surrounded by a valve seat 11, which is adapted to be closed by the diaphragm 7. A gas inlet pipe 12 communicates with the 60 chamber 10, and an outlet pipe 13 communicates with the chamber 9. A passage way 14 connects the pipe 12 with the inner chamber 10.

A downturned flange 15 provides a means 65 for securing the valve to a supporting structure 16 as by means of screws 17.

The pipe 13, conveying gas, projects it into a gas burner 18, shown in dotted lines in Fig. 2.

Secured substantially in the center of the cover 6 is a pipe 19 containing an expansible fluid 20. The pipe terminates in a receptacle 22. The receptacle 22 may be substantially circular and slightly concave to 75 fit against the rounded surface of the vessel to which it may be applied, as shown in Fig. 1, and it may have ears 23—23 to which a wire, or the like, 24 may be attached to hold it in intimate contact with said vessel; or 80 other means may be employed for this purpose, as shown in the modification of Fig. 4, which is to be hereinafter described.

The diaphragm 7 is secured to an annular ledge or washer 26 in the chamber 8, above 85 the diaphragm, as by solder or the like, 27, and in its normal, unrestrained position, as when all of the parts occupy the same horizontal plane under equalized pressure, it will neatly overlie the port 11 of the chamber 10, 90 and close the port against passage of gas from pipe 12 to pipe 13. The diaphragm 7 is shown slightly curved upward, in Fig. 2, that is to say it is pressed upwardly toward the upper portion of the cover 6, and this is 95 its normal operative position.

In the manufacture of the device, after the diaphragm has been placed in and hermetically secured to the cover 6, as described, and the chamber 8, the pipe 19 and the receptacle 22 have been filled with the heat responsive, expansible material 20 (the pin 28 having been removed from the receptacle 22,) the cover with its attached parts is placed in a suitable liquid such as water and 100 the liquid is heated up to a high temperature, say to the boiling point, whereby some of the contents 20 of the chamber 8, the pipe 19

and the receptacle 22, as a result of its expansion due to the boiling process, will be expressed or forced out of the vessel constituted by these containers. Then while the 5 device and its contents are still heated to the boiling point, the tapered pin 28 is firmly driven into the receptacle 22 to provide an air tight closure. When the contents 20 of said vessel has thereafter cooled to normal 10 temperature, the liquid will contract and the atmospheric pressure will press the diaphragm into the position shown in Fig. 2, leaving the port connecting chambers 9 and 10 open, between the seat 11 and the diaphragm 7, so that gas may now freely pass 15 from the pipe 12 through the pipe 13 into the burner 18. The difference in the pressure on the diaphragm 7, between the outside atmospheric pressure or the pressure to 20 which the gas is subjected and the pressure within the containers of the expandible fluid 20, serves to hold the diaphragm deformed in its strained or inwardly curved position against the resiliency of said diaphragm or 25 other elastic force inherent in said vessel. Now if the fluid be heated to a temperature higher than normal, it will expand and thereby force the diaphragm 7 outwardly tending to close the port 11 against the action 30 of the outside pressure, and the extent to which the port will be closed will depend entirely upon the degree to which the contents 20 has been heated above normal temperature. Therefore the quantity of gas 35 that will pass through the thermostatic valve will be determined by the temperature to which the contents of said vessel has been heated.

The position of the diaphragm 7, with 40 reference to the valve seat 11, is determined by the relative pressures exerted upon the two sides of the diaphragm, *i. e.* by the outside pressure on the one side and the pressure exerted by the expansion of the fluid 45 on the other side.

Now if the receptacle 22, be placed in a position where it may be heated by the gas that is admitted into the burner 18, and controlled by the valve, a rise of temperature 50 of the heat responsive fluid 20 within the receptacle 22, as a result of the varying temperature, will serve to regulate the amount of gas that will flow into the burner, to produce the heat.

55 When the receptacle 22 is placed upon the outside of the coffee urn, such as shown in Fig. 1, and when it is held in intimate contact therewith, as by a binding wire 24, it will receive heat from the contents of the urn, and will operate to govern the quantity 60 of gas that flows into the burner that may be placed under the urn for the purpose of heating coffee, or the like.

Natural drafts of air, however, passing 65 near the receptacle 22 will serve, as ex-

traneous influences, to vary its temperature, independently of the contents of the urn, and for this reason I prefer to inclose the receptacle 22 in a casing, such as shown in Fig. 4, so as to protect it against the cooling 70 influences of drafts of air. To this end I provide a casing comprising side walls 30—30, and similar end walls,—not shown,—the lower end wall being perforated suitably for the passage of the pipe 19 therethrough, 75 and inclose the receptacle 22 within said casing. A spring 31 is secured to one side, 80 wall of the casing for the purpose of pressing the receptacle 22 into intimate contact with the outer surface of the coffee urn.

To hold the casing in proper contact with the outside of the urn I perforate the walls 30—30, as at 33, and pass a wire, or ribbon 24, through said perforations, and on the inside of the casing I attach a spring 35 to 85 each end of the wire, or ribbon, as an elastic means for holding the wire or ribbon taut, for pressing the casing into intimate contact with the outer surface of the coffee urn.

Between the side walls 30—30 I place a 90 cover or cover plate 36, upon which the name of the device and of the manufacturer may be engraved or embossed. By this means I surround the receptacle 22 with a considerable air space, on each of its exposed sides, 95 so as to practically insulate the receptacle from extraneous influences.

It is of course manifest that the heat sensitive device may be placed in other environments than that shown in Figs. 1 and 4, but 100 I prefer under all conditions of use to have it influenced by the heat evolved from the gas that passes through the valve which the device controls.

Should the pipe 19, the receptacle 22 or the 105 casing 5, above the diaphragm, leak at any place, at any time, so that the contents thereof loses its less-than-atmospheric pressure and becomes subjected to atmospheric pressure, and the diaphragm 7 is thereby subjected 110 interiorly to atmospheric pressure, the diaphragm will, under such conditions, return to its normal horizontal position, in which plane the valve seat 11 is located, by the resilient effect of the diaphragm itself, 115 since the internal pressure on said diaphragm is less than the external pressure thereon substantially throughout the range of movement of said diaphragm. Thereby the valve is closed, preventing gas from passing 120 through the thermostatic device into the burner 18, automatically shutting off the gas in case of derangement, and eliminating the danger that would otherwise result from an unlimited supply of gas to the burner 125 when not subject to control of my thermostatic device.

By subjecting one side of the diaphragm to less-than-atmospheric pressure and the other side to atmospheric pressure or the 130

pressure of the gas, I attain a very sensitive and positively operating valve-controlling mechanism, and introduce a safety element into the device which will invariably operate to shut off the gas in the event of a leak of the vessel containing the heat responsive fluid.

Obviously a spring, interiorly or exteriorly of said vessel, tending to move the diaphragm toward safety position, may be substituted for the elasticity of a resilient wall.

Having described my invention, what I desire to secure by Letters Patent is:—

1. In a device for automatically controlling the flow of a medium through a conduit, a thermostatic vessel having a movable wall adapted to be flexed against an elastic force inherent in said vessel, a thermosensitive fluid sealed in said vessel and exerting an internal pressure on the movable wall below the opposing pressure of the external medium on said wall, the said movable wall bearing such relation to said conduit as to control the flow of the medium therethrough upon rise or fall of temperature and to effect therein a predetermined condition of safety upon the occurrence of a leak in said thermostatic vessel.

2. In a device for automatically controlling the flow of a medium through a conduit, the combination of a valve mechanism controlling said conduit, one position of which is a position of safety, and an expansible and collapsible vessel collapsible against an elastic force inherent in said vessel and having a thermosensitive fluid sealed therein, said fluid exerting an internal pressure below the opposing pressure of the external medium acting on said vessel, said vessel being operatively related to said valve mechanism to move the latter toward its position of safety upon the expansion of the vessel, whereby the valve mechanism will be operated by a rise or fall of temperature and moved to a position of safety upon the occurrence of a leak in said thermostatic vessel.

3. In a device for controlling the flow of a medium through a conduit, a valve mechanism, one position of which is a position of safety, a thermostatic vessel operatively related to said valve mechanism and having a resilient wall, and a thermosensitive fluid sealed in said vessel and exerting an internal pressure on said resilient wall below the pressure of the external medium thereon, said valve mechanism assuming its position of safety upon equalization of the pressures within and without said vessel.

4. In a device for controlling the flow of a fluid through a conduit, a valve mechanism comprising a valve port controlling said conduit, one position of said valve mechanism being a position of safety, a thermostatic vessel operatively related to said valve mech-

anism and having a resilient wall, and a thermosensitive fluid sealed in said vessel under a pressure below that of the surrounding medium, said vessel controlling said valve port in response to temperature variations in said fluid and causing said valve mechanism to assume its position of safety upon equalization of the internal and external pressures on said vessel.

5. In a device for controlling the flow of a medium through a conduit, a valve mechanism comprising a valve port controlling said conduit, one position of said valve mechanism being a position of safety, a thermostatic vessel operatively related to said valve mechanism and comprising a movable wall displaceable against an elastic force inherent in said vessel, and a thermosensitive fluid sealed in said vessel under a pressure below the external pressure thereon, said movable wall controlling said valve port in response to temperature changes in said fluid and said valve mechanism assuming its position of safety upon equalization of the internal and external pressures on said movable wall.

6. In a device for controlling the flow of a medium through a conduit, a valve mechanism comprising a valve port controlling said conduit, one position of said valve mechanism being a position of safety, a thermostatic vessel operatively related to said valve mechanism and having a wall deformable against an elastic force inherent in said vessel, and a thermosensitive fluid sealed in said vessel under a pressure below the external pressure thereon, said vessel controlling said valve port in response to temperature variations in said fluid and causing said valve mechanism to assume its position of safety upon equalization of the internal and external pressures on said vessel.

7. In a device for controlling the flow of a medium through a conduit, a valve mechanism comprising a valve port controlling said conduit, one position of said valve mechanism being a position of safety, a thermostatic vessel operatively related to said valve mechanism and subjected to the heating influence of the medium flowing through said conduit, said vessel having a wall deformable against an elastic force, and a thermosensitive fluid sealed in said vessel under a pressure below the external pressure thereon, said vessel controlling said valve port in response to temperature variations in said fluid and causing said valve mechanism to assume its position of safety upon equalization of the internal and external pressures on said vessel.

8. In a device for controlling the flow of a medium through a conduit, a valve mechanism comprising a valve port controlling said conduit, the closed position of said valve mechanism being a position of safety,

a thermostatic vessel operatively related to said valve mechanism and having a wall deformable against an elastic force inherent in said vessel, and a thermosensitive fluid sealed in said vessel under a pressure below the external pressure thereon, said vessel proportionately opening and closing said valve port in response respectively to temperature decreases and increases in said fluid and closing said port upon equalization of the internal and external pressures on said vessel.

9. In a device for controlling the flow of a medium through a conduit, a valve mechanism comprising a valve port controlling said conduit, one position of said valve mechanism being a position of safety, a thermostatic vessel operatively related to said valve mechanism and having a wall deformable against an elastic force inherent in said vessel, and a thermosensitive fluid sealed in said vessel, said fluid exerting an internal pressure on said vessel less than the external pressure thereon substantially throughout the operative range of movement of said valve mechanism, and said vessel controlling said valve port in response to temperature variations in said fluid and causing said valve mechanism to assume its position of safety upon equalization of the internal and external pressures on said vessel.

10. In a device for controlling the flow of a medium through a conduit, a valve mechanism comprising a valve port controlling said conduit, the closed position of said valve mechanism being a position of safety, a thermostatic vessel operatively related to said valve mechanism and subjected to the heating influence of the medium flowing through said conduit, said vessel having a wall deformable against an elastic force inherent in said vessel, and a thermosensitive fluid sealed in said vessel under a pressure below the external pressure thereon, said vessel proportionately opening and closing said valve port in response respectively to temperature decreases and increases in said fluid and closing said port upon equalization of the internal and external pressures on said vessel.

11. In a device for controlling the flow of a medium through a conduit, a valve mechanism comprising a valve port controlling said conduit, one position of said valve mechanism being a position of safety, a thermostatic vessel operatively related to said valve mechanism and subjected to the heating influence of the medium flowing through said conduit, said vessel having a wall deformable against an elastic force inherent in said vessel, and a thermosensitive fluid sealed in said vessel, said fluid exerting an internal pressure on said vessel less than the external pressure thereon substantially

throughout the operative range of movement of said valve mechanism, and said vessel controlling said valve port in response to temperature variations in said fluid and causing said valve mechanism to assume its position of safety upon equalization of the internal and external pressures on said vessel.

12. In a device for controlling the flow of a medium through a conduit, a valve mechanism comprising a valve port controlling said conduit, the closed position of said valve mechanism being a position of safety, a thermostatic vessel operatively related to said valve mechanism and having a wall deformable against an elastic force inherent in said vessel, and a thermosensitive fluid sealed in said vessel, said fluid exerting an internal pressure on said vessel less than the external pressure thereon substantially throughout the operative range of movement of said valve mechanism, and said vessel proportionately opening and closing said valve port in response respectively to temperature decreases and increases in said fluid and closing said port upon equalization of the internal and external pressures on said vessel.

13. In a device for controlling the flow of a medium through a conduit, a valve mechanism comprising a valve port controlling said conduit, the closed position of said valve mechanism being a position of safety, a thermostatic vessel operatively related to said valve mechanism and subjected to the heating influence of the medium flowing through said conduit, said vessel having a wall deformable against an elastic force inherent in said vessel, and a thermosensitive fluid sealed in said vessel, said fluid exerting an internal pressure on said vessel less than the external pressure thereon substantially throughout the operative range of movement of said valve mechanism, and said vessel proportionately opening and closing said valve port in response respectively to temperature decreases and increases in said fluid and closing said port upon equalization of the internal and external pressures on said vessel.

14. In a device for controlling the flow of a medium through a conduit, a valve mechanism comprising a valve port controlling said conduit, one position of said valve mechanism being a position of safety, a thermostatic vessel operatively related to said valve mechanism and comprising in the walls thereof a diaphragm adapted to be flexed against an elastic force inherent in said vessel, and a thermosensitive fluid sealed in said vessel under a pressure below the external pressure thereon, said vessel controlling said valve port in response to temperature-variation in said fluid and causing said valve mechanism to assume its safety

position upon equalization of the internal and external pressures on said diaphragm.

15. In a device for controlling the flow of a heating medium through a conduit, a valve port, a thermostatic vessel comprising in the walls thereof a diaphragm adapted to be flexed against an elastic force inherent in said vessel and coacting with said port to control the flow of medium therethrough, the closing of said port presenting a condition of safety, and a thermosensitive fluid sealed in said vessel under a pressure below the external pressure thereon, said diaphragm controlling the flow of heating medium through said conduit in response to temperature variations in said fluid and closing said port upon equalization of the internal and external pressures thereon.

16. In a device for controlling the flow of a medium through a conduit, a valve mechanism comprising a valve port controlling said conduit, one position of said valve mechanism being a position of safety, a thermostatic vessel comprising a receptacle subjected to the heating influence of said medium and operatively related to said valve mechanism, a wall of said vessel being deformable against an elastic force inherent in said vessel, and a thermosensitive fluid sealed in said vessel under a pressure below the external pressure thereon, said vessel controlling said valve port in response to temperature variations in said fluid and causing said valve mechanism to assume its safety position upon equalization of the internal and external pressures on said vessel.

17. In a device for controlling the flow of a heating medium through a conduit, a valve

mechanism comprising a valve port controlling said conduit, one position of said valve mechanism being a position of safety, a thermostatic vessel comprising a receptacle subjected to the heating influence of said medium and a container in communication with said receptacle having a wall deformable against an elastic force inherent in said vessel, and a thermosensitive fluid sealed in said vessel under a pressure below the external pressure thereon, said vessel controlling said valve port in response to temperature variations in said fluid and causing said valve mechanism to assume its safety position upon equalization of the internal and external pressures on said vessel.

18. In a device for controlling the flow of a medium through a conduit, a valve mechanism comprising a valve port controlling said conduit, one position of said valve mechanism being a position of safety, a thermostatic vessel operatively related to said valve mechanism and comprising a movable wall displaceable against an elastic force, and a thermosensitive fluid sealed in said vessel under a pressure below the external pressure thereon, said movable wall controlling said valve port in response to temperature changes in said fluid and said valve mechanism assuming its position of safety upon equalization of the internal and external pressures on said movable wall.

In testimony whereof I hereunto set my hand in the presence of two witnesses.

NOAH S. HARTER.
